The ornamental design for a waste receptacle, substantially as shown and described.

DESCRIPTION

FIG. 1 is a front, raised perspective view of a waste receptacle according to the invention; FIG. 2 is a front view of the waste receptacle of FIG. 1; FIG. 3 is a rear view of the waste receptacle of FIG. 1; FIG. 4 is a right side view of the waste receptacle of FIG. 1; FIG. 5 is a left side view of the waste receptacle of FIG. 1; FIG. 6 is a top view of the waste receptacle of FIG. 1; FIG. 7 is a bottom view of the waste receptacle of FIG. 1; and, FIG. 8 is a front, lowered perspective view of the waste receptacle of FIG. 1.

The broken lines shown in the drawings form no part of the claimed design. All surfaces not shown form no part of the claimed design. Further, the waste receptacle is shown with symbolic breaks in its width. The appearance of any portion of the waster receptacle between the break lines forms no part of the claimed design.
